UNITED STATES PATENT OFFICE

GOTTHARD BAURIEDEL, OF BARMEN, AND WILLI FICHTHORN, OF ELBERFELD, GERMANY, ASSIGNORS TO THE FIRM AMERICAN BEMBERG CORPORATION, OF NEW YORK, N. Y.

FASTENING DEVICE FOR SPINNING CENTRIFUGES USED IN THE PRODUCTION OF
ARTIFICIAL SILK

Application filed December 13, 1928, Serial No. 325,681, and in Germany December 19, 1927.

In the production of artificial silk, so-called spinning centrifuges or spinning pots are employed for simultaneously collecting and twisting the thread obtained, the thread 5 being laid upon the wall of the centrifuge under the action of centrifugal force and twisted simultaneously by the rotation of the centrifuge. Spinning pots of this kind are rotated at a very high speed. Careful 10 centring of the pots is, therefore, essential in order to avoid vibration. Further, it is important that the spinning pots may be easily and quickly mounted upon their driving shafts and also removed therefrom. 15 The invention relates particularly to spinning pots, in which an open spinning pot, having at the bottom an opening for the introduction of the thread, is set up in an inverted position upon a disc on the driving 20 shaft. In spinning pots of this kind, it has already been proposed to fasten the conical pot to the conical rim of the plate by means of an inserted indiarubber ring. The indiarubber ring was to be square in cross-section. 25 A flange on the bottom of the driving plate served to limit the height that the pot projected above the plate. This kind of fastening has the disadvantage that it is extraordinarily difficult, if not impossible, to 30 set the pot simultaneously on the indiarubber ring and upon the supporting plate. This is, however, necessary in order that the pot may be driven with certainty by the driving plate. 35 The disadvantage described is avoided according to the invention, by employing an indiarubber ring of circular cross-section serving to fasten and centre the pot upon the driving plate, and which runs along on the 40 driving plate and the spinning pot while the spinning pot is being set up. Thus, rolling friction replaces the sliding friction which occurs in the known device while the spinning pot is being set up. By this means, 45 the operation of setting up the pot is facilitated. Further, it is possible to allow the indiarubber ring to run over a track of varying diameter or a conical path on the spinning pot or driving disc and thus effect a 50 gradual compression of the ring, without the

operation of setting up the pot being made difficult.

Grooves are preferably formed in the spinning pot or the driving plate to receive the indiarubber ring. These grooves are so shaped, however, that the setting up of the spinning pot until it is pushed down on to the driving plate is not made difficult. 55

Two constructional forms of a spinning pot in accordance with the invention are illustrated in section in the accompanying drawings, in which:— 60

Figure 1 shows a form of construction in which the spinning pot has a smooth surface and the driving plate has a profiled surface; 65 and

Figure 2 shows a form of construction in which the driving plate has a smooth surface and the spinning pot has a profiled surface. 70

In Figure 1, the spinning pot 1 is carried by a plate 2 mounted upon the shaft 3 of the driving motor 4. The shaft 3 passes through the bottom of the spinning pot casting 5, part only of which is illustrated. 75

The rim of the driving plate 2 is so shaped that there are two grooves 6 and 7 for an indiarubber ring 8, between which grooves there is a swelling 9.

The indiarubber ring 8 takes up the position 8' shown in dotted lines before the spinning pot is pushed down over the plate 2. When the spinning pot is pushed over the plate 2, the ring rolls out of the groove 6 over the swelling 9 into the groove 7. As the groove 7 is made more shallow than the groove 6, the indiarubber ring by this means may be definitely compressed to a certain extent. The spinning pot at the point 10 is once more accurately centred upon the driving plate 2. 80

In the form of construction according to Figure 2, the method of securing is fundamentally the same, only the grooves 6 and 7, 95 with the intervening swelling 9, are formed on the spinning pot. To correspond with this, the rim 11 of the driving plate 2 is not turned downwards but upwards. The definite centring of the spinning pot in the 100

driving plate 2 is effected by means of the flange 12.

Before the commencement of the insertion of the pot, the indiarubber ring takes up the 5 position 8' on the pot, shown in dotted lines.

What we claim is:—

1. The combination with a spinning pot and a driving plate of a fastening for the spinning pot, comprising an elastic ring between a surface of the spinning pot and a concentric surface of a driving plate, and a grooved rolling track upon one of said surfaces, said elastic ring being adapted to be rolled into a groove in said rolling track as 15 the spinning pot is being set up upon the driving plate to secure a good driving connection.

2. The combination with a spinning pot and a driving plate of a fastening for the 20 spinning pot, comprising an elastic ring between the spinning pot and a surface of the driving plate concentric therewith, and a grooved rolling track upon said driving plate, said elastic ring being adapted to be positioned in one groove at the commencement 25 of the operation of setting up the spinning pot upon the driving plate and to be rolled into a second groove as the spinning pot is being set up upon the driving plate to 30 secure a good driving connection.

3. The combination with a spinning pot and a driving plate of a fastening for the spinning pot, comprising an elastic ring between the spinning pot and a surface of the 35 driving plate concentric therewith, a rolling track upon the driving plate having two grooves, one of which is more shallow than the other, said elastic ring being adapted to be initially in the deeper groove and to 40 roll into the more shallow groove as the spinning pot is being set up upon the driving plate to secure a good driving connection.

4. The combination with a spinning pot 45 and a driving plate of a fastening for the spinning pot, comprising an elastic ring between a surface of the spinning pot and a surface of the driving plate concentric therewith, and an inclined track upon one of 50 said surfaces adapted to compress the elastic ring and roll it into a groove as the spinning pot is set up upon the driving plate, said groove being of such dimensions that the elastic ring will be compressed between the spinning pot and the driving 55 plate to secure a good driving connection.

5. The combination with a spinning pot and a driving plate of a fastening for the spinning pot, comprising an elastic ring between 60 the spinning pot and a surface of the driving plate concentric therewith, said ring being adapted to roll along surfaces of the spinning pot and the driving plate into a groove in one of said surfaces as the spinning pot is being set up upon the driving 65 plate, and being adapted when in the groove to secure a good driving connection and co-operate with a surface of the driving plate contacting with a surface of the spinning pot to center the spinning pot.

In testimony whereof we affix our signatures.

GOTTHARD BAURIEDEL.
WILLI FICHTHORN.
